M. ASHERMAN

ATTACHMENT FOR LADIES' BAGS

Filed July 12, 1926

MAX ASHERMAN

INVENTOR

BY *Ottoman*

his ATTORNEY,

UNITED STATES PATENT OFFICE.

MAX ASHERMAN, OF NEW YORK, N. Y.

ATTACHMENT FOR LADIES' BAGS.

Application filed July 12, 1926. Serial No. 121,779.

My invention relates to improvements in a glove or handkerchief holder for ladies' hand bags.

Briefly the object of the invention is to provide a hand bag or similar article with a reenforced strap or flap which is so connected with the bag that it may be engaged over a pair of gloves, handkerchief, etc., and fastened by a separable fastening means to a section of the bag proper.

The invention is illustratively exemplified in the accompanying drawings in which Figure 1 is a perspective view of one embodiment of my invention; Figure 2 is a perspective view of a modification; Figure 3 is a perspective view of the holder for the hand bag; and Figure 4 is a perspective view of the reenforcing member used in the holder.

Referring to the drawings, 10 denotes the front or rear walls of the usual pouch type hand bag having their adjacent bottom and side edges stitched together and the free edges at the top of the bag provided with the ordinary frame 11 and handle 12. In Figure 1 the invention is shown applied to the back wall and comprising a strip of material in the form of a tab 13 which is connected to the bag proper along the bottom seam thereof so as to fold upwardly over the face of the back wall 10. The tab itself comprises at least two superimposed layers of leather or fabric, the outer layer being turned over the under layer and a line of stitching 14 run marginally about the tab, as illustrated in Figure 3. The layers are reenforced and provided with upstanding ribs or engaging jaws 15 formed by a substantially U-shaped metal strip 16 disposed between the two layers of material with the upstanding sides directed towards the inside layer. When the tab is made the inside layer of material is worked over the metal strip 16 so as to give the inside surface of the tab the appearance of merely having two outwardly projecting ribs or jaws running parallel with the sides of the tab. The free end of the tab is provided with one member of a separable fastening means 17, while the other member is carried by the adjacent wall of the bag.

Application of the invention to the flat type bag illustrated in Figure 2, requires no change in the design of the tab 13, the latter being connected to the front wall 10

of the bag at a point adjacent the lower edge thereof. In this arrangement the wall of the bag is slit lengthwise and the end of the tab inserted and secured. To finish off the work a small strap or band 18 is arranged over the slit. When the tab is arranged on the front wall of the bag and the latter is of the flat type having a folding flap 19 to close over the open end of the bag, it is desirable to provide the tab itself with one member of a separable fastening means 20, the other member being carried by the flap 19 in the usual manner. Therefore, when the bag is closed the flap 19 is held in place by its connection with the tab.

To utilize the present invention it will be clear that the tab 13 is merely unfastened at the separable fastening means 17 and the gloves or handkerchief placed against the adjacent wall of the bag and the tab folded thereover and engaged again. The outstanding jaws 15 of the tab engage and press transversely into the articles being held to prevent the latter being easily removed without disengaging the fastening means.

Having now described the nature of my invention what I claim as new and desire to secure by Letters Patent is:—

1. An attachment for a hand bag, comprising a tab permanently connected at one end to the bag and separably connected thereto at the free end, said tab being provided with outstanding rigid ribs on its inner face to engage articles placed between the tab and bag.

2. An attachment for a hand bag, comprising a tab permanently connected at one end to the bag and separably connected thereto at the free end, said tab comprising layers of material, and a reenforcing member disposed therebetween having upstanding ribs over which portions of one layer are made to conform, said covered rib forming jaws directed towards the wall of the bag when in closed position.

3. In combination with a hand bag having a closing flap, of a glove holding attachment for the bag comprising a tab permanently connected at one end to the outer wall of the bag and separably connected thereto at its free end, said tab and flap each carrying members of a separable fastening means, whereby when the bag is closed the flap is connected to the tab.

4. An attachment for a hand bag, com-

prising a tab permanently connected at one end to the bag and separably connected thereto at the other end, said tab comprising layers of material attached together along their edges, and a metal insert disposed between the layers and comprising a rigid strip of metal having its longitudinal

edges upturned in lines substantially parallel to the sides of the tab, the ribs formed by the upturned edges being directed towards the wall of the bag when the tab is in closed position. 10

In testimony whereof I affix my signature.
MAX ASHERMAN.
